UNITED STATES PATENT OFFICE.

WILLIAM T. HORMES, OF CATONSVILLE, MARYLAND.

DESIGN FOR A GRILLE.

Application filed November 22, 1927. Serial No. 24,235. Term of patent 3½ years.

To all whom it may concern:

Be it known that I, WILLIAM T. HORMES, a citizen of the United States, residing at Catonsville, in the county of Baltimore and State of Maryland, have invented a new, original, and ornamental Design for Grille, of which the following is a specification, reference being had to the accompanying drawing, forming part thereof.

The figure is a front elevation of a grille illustrating the design of the invention.

I claim:—

The ornamental design for a grille, as shown.

WILLIAM T. HORMES.
